DISK HARROW

Frank Henry Dutra, Campbell, Calif.

Application October 21, 1935, Serial No. 45,851

4 Claims. (Cl. 55—83)

My invention relates to improvements in cultivators and the object of my improvement is to provide a harrow of unusually simplified construction, but also very rugged and efficient. 5 Further objects are to provide means of rapid adjustment and a novel arrangement of the gangs. Still further objects will appear from the description.

In the drawings:

10 Figure I is a top view of the entire disk harrow, Fig. II is a side view, partly in section, of the frame,

Fig. III is an end view of a rear gang,

Fig. IV is a detail of frame construction,

15 Fig. V is a top view showing the gangs in parallel adjustment.

The disks 1, mounted upon axles 2, are arranged in four gangs, two in front and two behind, and are held in position by supports 3 bolted to the upper frame by bolts 4 and 5.

20 On the rear gangs the bolts 4 pass through slots 6 so that the axles 2 may be shifted into or out of parallelism with the upper frame, and so give the disks of the rear gangs greater or less plow action than those of the front gangs.

25 In the frame is a zigzag steel plate 7 to which are attached one front and one rear gang, and a similar plate 8 to which are attached the other front and rear gangs. The plates 7 and 30 8 cross at the center and are held together by a single kingbolt 9 which allows a scissors-like action between them.

35 A steel strip 10 lies above and a second strip 11 below the central portion of plates 7, 8. These strips 10, 11 are held apart by sleeves 12 upon the bolts 13 which fasten them together.

Upon the kingbolt 9 is a sleeve similar to that upon bolt 13 but designed to act as a bearing at the point of greatest strain when the harrow 40 is being drawn forward.

A tongue 14, bolted at the rear to strips 10, 11, is drilled with several holes 15, and slidably held in front between the transverse plate 16 and the drawbar 17. Bolts 18 serve to hold together the 45 plate and drawbar and also act as guides for the tongue 14. The transverse plate 16 is attached to the forward ends of the zigzag plates 7 and 8 by links 19 and 20.

For deep cutting, the gangs are arranged at 50 oblique angles to the direction of pull; for shallow cutting at right angles. Adjustment is made by removing pin 21 and backing up the tractor. The drawbar 17 and the attached plate 16 then

slide back on the tongue 14 and the pin 20 is inserted in another of the holes 15 to give the desired angle.

Pushing back the plate 16 spreads the attached links 19 and swings the zigzag plates 7 and 8 into a more parallel position as shown in Figure V. To facilitate adjustment washers or ball bearings 22 are provided between the plates 7 and 8.

1 claim:

1. A disk harrow having a frame plate with parallel end portions joined by a central portion at an oblique angle to the end portions, a second frame plate similar to the first but reversed and crossing it, ball bearings between said frame plates, a pivotal bolt joining together the centers of said frame plates, a sleeve bearing upon said bolt, gangs of disks beneath said frame plates, longitudinal strips above and below the central portions of said frame plates and penetrated by 20 said pivotal bolt, sleeved bolts separating said strips, a tongue attached to said strips, adjusting holes in said tongue, a sliding member upon said tongue, a pin passing through said sliding member and any one of the adjusting holes in 25 said tongue, and links joining said sliding member to the forward ends of said frame plates.

2. A harrow having in combination diagonally crossed frame members, gangs of disks rigidly and longitudinally attached to opposite ends of 30 said frame members, a pivotal bolt fastening together said crossed members, and means for adjusting the angle between said crossed members.

3. A harrow having crossed frame plates, a 35 longitudinal strip running forward from the point of crossing of said plates, a pivotal bolt fastening together said crossed plates and said strip, gangs of disks rigidly attached to said crossed plates, a slideable member upon said longitudinal strip, a pin passing through said strip and said slideable member, and links joining said slideable member and the forward ends of said frame plates.

4. A disk harrow having two crossed frame members, each with parallel end portions joined by central portions integral therewith and at obtuse angles thereto, disk gangs attached to 40 said frame members, means for changing the angle between said crossed frame members, and draft means attached to said frame members.

FRANK HENRY DUTRA.
